CLAIM

The ornamental design for an adjustable standing lamp,
as shown and described.

DESCRIPTION

FIG. 1 is a top and left perspective view of an adjustable standing lamp showing my new design;
FIG. 2 is a bottom and right side perspective view thereof;

FIG. 3 is a rear elevational view thereof;

FIG. 4 is a side elevational view thereof, the opposite
side being a mirror image;

FIG. 5 is a top plan view thereof; and

FIG. 6 is a front elevational view thereof.
